UNITED STATES PATENT OFFICE.

GEORGE HILLARD BENJAMIN, OF NEW YORK, N. Y.

METHOD OF OPERATING METALLURGICAL FURNACES.

1,033,777.

Specification of Letters Patent. Patented July 30, 1912.

Application filed June 17, 1911. Serial No. 633,738.

To all whom it may concern:

Be it known that I, GEORGE HILLARD BENJAMIN, a citizen of the United States, residing at New York city, in the county 5 and State of New York, have invented certain new and useful Improvements in Methods of Operating Metallurgical Furnaces, of which the following is a specification.

My invention consists in a method of operating metallurgical furnaces of the general type described in U. S. Letters Patents granted to Robert Hubner of New York, Nos. 899,403 dated September 22nd, 1908; 906,883 dated December 15th, 1908, 15 934,532 dated September 21st, 1909, and the improvements described herein.

The feature of novelty in the method of operation described in the present application over that set forth in the patents mentioned, 20 is found in the fact that instead of feeding the material into the top of the furnace to be moved progressively downward from chamber to chamber until the bottom of the furnace is reached, provision is made 25 for feeding the material to be acted upon into any of the chambers and then advancing it downward, thus permitting the material to be primarily acted upon at any desired temperature. Further, instead of acting 30 upon the material wholly by heat, as in the above mentioned patents, provision is made for introducing into any of the chambers, such gases or fluxing materials as may be useful or necessary to effect 35 chemical reactions with the materials treated, at specific temperatures, thus bringing about metallurgical results which cannot be obtained by the methods of operation described in the patents mentioned.

40 The accompanying drawings will serve to illustrate such a construction as may be used to carry my improved method of operation into effect, in which—

Figure 1 is a vertical longitudinal section. Fig. 2 is a vertical transverse section on the line II—II of Fig. 1. Fig. 3 is a vertical transverse section on the line III—III of Fig. 1. Fig. 4 is a longitudinal section on the line IV—IV of Fig. 1. Fig. 5 is a view corresponding to Fig. 1 with the dampers that control the heating flues in a different position.

In the drawings, 5 indicates the furnace structure; 6, grate; 7, combustion chamber. 55 The combustion chamber 7 communicates through the horizontal flue 8, directly with

the chimney flue 9, and indirectly through the horizontal flues 10, 11, 12, 13, 14, and vertical flues 15, 16, with the chimney flue 9. Located in the flues are dampers or valves 60 17, by manipulating which the direction of the hot air current may be regulated.

Located at one side of the furnace, are gas and air pipes 18 and 19, through which gas and air in a mingled condition may be 65 fed to the horizontal flues 8, 10, 11, 12, 13, 14, through the instrumentality of burners 20, the ingress of the gas and air being controlled by valves 21, 22. Preferably the gas and air is under pressure. By manipulating 70 the dampers 17, any of the treating chambers A, B, C, D, E, F, may be isolated. The treating chambers are disposed between the heating flues, and connected to each treating chamber alternately on opposite 75 sides of the furnace, are hoppers 25, provided with a rotary valve 26. A pusher, 27, is located under the hopper. Only four hoppers are shown corresponding to four chambers. A hopper, however, may be used 80 in connection with each chamber. The operation of the hoppers and pusher are well understood, and no description is necessary.

Located on one side of the furnace, is an 85 exhaust pump 30, which is connected through its induction orifice to a pipe 31, itself connected through branch pipes 32 to treating chambers A, B, C, D, E, F. Each of the branch pipes 32 is provided with a 90 valve 33, so that the pump 30 may act on any one or all of the chambers as desired.

35 indicates a gas pump, connected through its induction orifice with a pipe 36, from which lead branch pipes 37, 38, 39, 40, 95 to sources of gas which may vary, as for instance, a source of oxygen, hydrogen, chlorine, cyanogen, acetylene, or a source of a pulverized product or bodies, such for instance as carbon, lime, calcium carbide, calcium fluorid, magnesia, or any other body which may be employed to produce chemical reactions alone or in connection with a gas or gases, when brought into contact with the ore in any chamber at any required temperature. Suitable valves 41 are provided in the branch pipes. The eduction orifice of the gas pump 35 is connected to a pipe 42 connected by branch pipes 43 to the treating chambers A, B, C, D, E, F. 44 indicates 100 suitable valves in these pipes.

The treating chambers A, B, C, D, E, F,

are shown as connected through passages G. The passages G are controlled by valves H, which may be opened to permit communication between the chambers, as for instance, 5 between A and B, or to shut off communication, as shown between C and D.

I wish it understood that I do not limit myself to the particular construction shown for the furnace as a whole. The distribution 10 of the flues, chambers, air passages, valves, heat producing means, exhaust apparatus, or gas and flux feeding apparatus (it will be understood by those skilled in the art) may be changed, without departing 15 from the intent of the invention.

The operation of the furnace will be understood by metallurgists without the necessity of an extended description, as it will be understood, that to describe all of the actions 20 and reactions which can be caused to take place in a furnace having the characteristics disclosed, would be merely to recite well known metallurgical operations.

Generally stated, the operation of the furnace 25 is as follows: Ore is charged by one of the hoppers 25, into the chamber A, pushed in by the pusher 27, and after a time under the action of the pusher, discharged through passage G into chamber B, and so on progressively downward until finally discharged from the furnace through suitable openings provided in the walls; manifestly, instead of charging the ore into the chamber A, it may be charged into any of the 30 chambers, depending upon the initial temperature to which it is desired the ore shall be subjected, it being understood that the temperature of the chambers A, B, C, D, E, F, is normally greater from the top to the 35 bottom of the furnace. This, however, may be reversed by varying the gas flames, through the burners 20. During the time that the ore is in the treating chambers or in any one of the chambers, the exhaust 40 pump 30 is preferably in operation. The action of the pump is to draw the evolved gases out of the chamber and thus remove any pressure from the ore, thereby permitting free evolution of gas. If desired, the ore may be subjected to any required temperature without exhaustion of the gases, the process being an intermittent one, that is, the ore may be subjected to a temperature 45 without the exhaustion of the gases, then to a different temperature with exhaustion of the gases.

In certain metallurgical operations it is desirable to subject the ore under treatment to the action of an introduced gas or flux, or to the action of several gases or several fluxes. These gases or fluxes are introduced through the gas pump 35, at any desired pressure. Manifestly, at the time the gases 50 or fluxes are introduced, exhaustion from the chamber or chambers will be discon-

tinued. Further, it is evident that a series of operations may be conducted in the furnace. In one chamber, for instance, treating ore without the introduction of gases or fluxes and without exhaustion. In the next 70 chamber, treating and exhausting the gases. In the next chamber, treating and introducing and combining the gases or fluxes,—and so on, varying as required to carry out the metallurgical operations desired.

In practice, it has been found that a plurality of different metallurgical operations may be carried on in the furnace at one time. Further, if desired, any two chambers may be brought into coöperation where two 75 metallurgical operations are in progress, the operation in one chamber reacting upon that in the other with beneficial results.

I do not wish to limit myself in any wise to the character of metallurgical operations 80 which may be carried on. It will be evident to those skilled in the art, to which this specification pertains, that a furnace constructed and operated as described, is capable of effecting a great many metallurgical 85 operations and with the greatest economy, and for the reason, that the heat employed in one operation (which ordinarily would wastefully be discharged into the atmosphere) will, through the construction described, be utilized in other operations carried on at the same time; and further, that the gas or gases used in one operation, or evolved in such operation, may be utilized 90 in carrying on other operations without loss 95 by contact with the atmosphere, or without loss of heat.

I have described my improved furnace as generally employed in the reduction of ores. It may, with great advantage, be employed 100 in the production of distillation products from coal. It is well known that products from coal are evolved at different temperatures, and that if segregated at the time they are evolved, may be utilized—but if 105 not separated, will combine with other products evolved at different temperatures to form other bodies. In my improved furnace, provision is made for extracting at the 110 time of separation, the product due to the temperature, or for the chemical treatment of the product while in a nascent state, i. e., at the time of separation from the coal, by the introduction of gases or combining 115 bodies.

I wish it understood that I consider, as a part of my invention, the utilization of the evolved gas or gases from any body at any temperature, as also the treatment of such evolved gas or gases, or the treatment of 120 the material from which such gas or gases are obtained.

In addition to the uses above described, my furnace may be employed in the treatment 125 of a large number of chemical bodies 130

to form secondary products, such as salt to form soda, the production of bodies derived from lead and zinc, conversion of sulfur into commercial products, phosphoric acid with lime to form a fertilizer, and other uses too numerous to mention, and which will readily appeal to industrial chemists.

Having thus described my invention, I claim:

- 10 1. The herein described method of operating a metallurgical furnace, which consists in charging the material to be treated into a chamber, subjecting it to a defined initial temperature for a definite time, exhausting the evolved gases, and introducing a combining body into such chamber.
- 15 2. The herein described method of operating a metallurgical furnace, which consists in charging the material to be treated into a chamber, subjecting it to a defined initial temperature for a definite time, exhausting the evolved gases, subjecting it to a different temperature for a definite time, and introducing a body which will combine at such change of temperature.
- 20 3. The herein described method of operating a metallurgical furnace, which con-

sists in charging the material to be treated into a closed chamber, subjecting it to a defined initially applied temperature for a 30 definite time, exhausting the evolved gases from said chamber, subjecting it to a change of temperature for a definite time, and introducing a body which will combine with the material in such closed chamber at such 35 change of temperature.

4. The herein described method of operating a metallurgical furnace, which consists in charging the material to be treated into a chamber having an initially defined 40 temperature, progressively feeding said material into successive chambers heated to higher temperatures, exhausting the evolved gases from said chambers, and subjecting the material to the action of introduced 45 bodies in such of said chambers where the temperature conditions are those which will effect the desired chemical combination.

In testimony whereof, I affix my signature, in the presence of two witnesses.

GEORGE HILLARD BENJAMIN.
